(57) **CLAIM**

The ornamental design for a “tooth pillow”, as shown and described.

DESCRIPTION

FIG. 1 is a perspective view of the tooth pillow;

FIG. 2 is a front view of the tooth pillow;

FIG. 3 is a rear view of the tooth pillow;

FIG. 4 is a top view of the tooth pillow;

FIG. 5 is a bottom view of the tooth pillow;

FIG. 6 is right side view of the tooth pillow; and,

FIG. 7 is left side view of the tooth pillow.

In the drawings, the broken lines represent stitching forming part of the claimed design.
